UNITED STATES PATENT OFFICE

108,052

DESIGN FOR A HANDBAG

Henri Felmann, Chicago, Ill.

Application December 20, 1937, Serial No. 73,723

Term of patent 3½ years

To all whom it may concern:

Be it known that I, Henri Felmann, a citizen of the United States of America, residing in Chicago, in the county of Cook, State of Illinois, have invented a new, original, and ornamental Design for a Handbag, of which the following is a specification, reference being had to the accompanying drawing, forming part thereof, wherein,

The rear portion of the handbag has an identical flap as the front, which rear flap is alternately arranged, as shown in Figure 3.

I claim:

The ornamental design for a handbag, substantially as shown and described.

HENRI FELMANN.
